Primary Examiner — Barbara Fox*Assistant Examiner* — Mehri F Bajoul(74) *Attorney, Agent, or Firm* — Thomas | Horstemeyer, LLP(57) **CLAIM**

The ornamental design for a pet tunnel, as shown and described.

DESCRIPTION

FIG. 1 is a front perspective view of a pet tunnel showing the new design;

FIG. 2 is another perspective view of the pet tunnel from a side opposite that of FIG. 1;

FIG. 3 is a side view of the pet tunnel;

FIG. 4 is a side view of the pet tunnel from a side opposite that of FIG. 3;

FIG. 5 is a front view of the pet tunnel;

FIG. 6 is a rear view of the pet tunnel from a side opposite that of FIG. 5;

FIG. 7 is a top view of the pet tunnel; and,

FIG. 8 is a bottom view of the pet tunnel.

The broken line shown in the drawings depict portions of the pet tunnel that form no part of the claimed design.

1 Claim, 8 Drawing Sheets(56)
